UNITED STATES PATENT OFFICE.

JAMES FRANK DURYEA AND WILLIAM MERRIAM REMINGTON, OF SPRINGFIELD, MASSACHUSETTS, ASSIGNORS TO STEVENS-DURYEA COMPANY, OF CHICOPEE FALLS, MASSACHUSETTS, A CORPORATION.

INTERNAL-COMBUSTION ENGINE.

No. 917,722.

Specification of Letters Patent.

Patented April 6, 1909.

Application filed February 12, 1908. Serial No. 415,508.

To all whom it may concern:

Be it known that we, JAMES FRANK DURYEA and WILLIAM MERRIAM REMINGTON, citizens of the United States of America, 5 residing at Springfield, in the county of Hampden and State of Massachusetts, have invented new and useful Improvements in Internal-Combustion Engines, of which the following is a specification.

10 This invention relates to internal combustion engines and especially to means to start a multiple cylinder engine having a jump spark ignition system without "cranking" the same; that is without being obliged 15 to rotate the crank-shaft one or more times to inspire or draw an explosive charge into the cylinders, the object of the invention being to provide means whereby a quantity of combustible may be introduced into the 20 cylinders of the engine above the piston, there being, in an engine of the type referred to, always one cylinder in which the piston has passed over the center on the compression stroke, thus enabling the combustible 25 to that cylinder to be ignited by a movement of the switch to close the ignition circuit after retarding the spark.

This invention is particularly adapted to 30 motors of the type specified as employed for propelling vehicles, and is thus illustrated in the accompanying drawings, a portion of the dash of a vehicle being shown in connection with the motor.

In the drawings forming part of this application,—Figure 1 is a side elevation of those 35 parts of a multiple cylinder motor necessary to a complete understanding of the invention which is shown applied thereto in its preferred form, certain of the parts being shown 40 in dotted lines. Fig. 2 is a side elevation of a fuel reservoir showing a modification of the construction of the conduits running to the cylinders. Fig. 3 is a sectional elevation of a valve having a charge-measuring pocket or 45 recess therein, the valve-plug being shown in two positions. Fig. 4 is a side elevation, partly in section, of the valve shown in Fig. 3, this view being taken at right angles to that shown in said last named figure.

50 Referring to these drawings, *a, a, a* indicate the cylinders of a motor; *b* the reservoir for the combustible, and *c, c* are pipes extending from the reservoir to the cylinders. Preferably, a separate pipe is used between each

cylinder and the reservoir, as shown in Fig. 1, 55 as this construction insures sufficient flexibility in these connections to avoid breakage or leaks which might otherwise arise from the vibration of the cylinders, the reservoir usually being secured to some near by rigid 60 support, as for instance to the dash *d*. If desired, however, a single conduit *e* may extend from the reservoir (as shown in Fig. 2) to the farthest cylinder, and be tapped at each cylinder, as at *f*, for a short pipe *g* extending therefrom to the cylinder.

A valve *h* (the preferred form of which is shown in Figs. 3 and 4) is threaded into the top of each cylinder, the pipes *c* being connected to the inlet end of these valves by a 70 flange coupling *k*, or otherwise. The most convenient form of valve to use for this purpose is an ordinary tapered plug-valve, as shown, and to insure a tight-fitting plug a spring *m* may be applied to it in the usual 75 way to hold it to its seat in the valve-body. As shown in Figs. 3 and 4 most clearly, the valve-plug is milled off on one side thereof to form a small pocket *p* between it and the body of the valve. On the plug is a crank-arm *q* and when this is swung to the position shown in dotted lines in these last named figures, the pocket *p* will be in communication with the passage *r* in the valve-body which is a continuation of the pipe *c*, and the pocket may therefore fill with the liquid fuel which will flow into it from the reservoir. Extending from the tapered hole in the valve-body, in which the plug is seated down through the lower end of the body, 90 are two passages *s* and *t*, the first of which communicates with the pocket *p* when the plug is in the position shown in section in Fig. 3, the second passage, when the plug is in this position, registering with the vent-hole *v* in the plug,—this hole in turn registering at its outer end with a hole *w* in the wall of the valve-body. An examination of the dotted position of the plug will show that when in that position the inner ends of 95 the two passages *s* and *t* will be sealed, thus cutting off all communication therethrough with the cylinder, the combustible in the pocket *p* being thereby protected against ignition. This is the normal position of the 100 valve in each cylinder.

It will be noted that the crank-arms *q* are each connected pivotally to a rod *x*, the end

- of which may extend through the dash within convenient reach of the operator, there being a hook or the like on the end of it whereby it may be moved endwise. Preferably the rod x is made in two parts, there being a short length x^1 extending through the dash and connected by a link y to the end of the rod x next to the dash, whereby there will be no binding effect on that part 10 extending through the dash when as the arms q swing through the highest point of their arc the rod is raised bodily more or less.

As stated, the normal position of the parts 15 is that shown in full lines in Fig. 1, in which position each of the pockets p in the plugs of the valves on the cylinders is in communication through the pipes c with the reservoir, the combustible flowing into the 20 pockets, (see dotted position in Fig. 3). When it is desired to start the motor the operator pulls the rod x to swing the crank-arms to the position shown in dotted lines Fig. 1, and the contents of each of the 25 pockets flows into the cylinders, and as in multiple cylinder motors some one of the pistons is always in position ready for the ignition of the combustible, it is only necessary to wait for a moment after having 30 actuated the valves to permit the volatili-

zation of the combustible before throwing the switch of the electric ignition system, to produce a spark in that one of the cylinders ready for ignition and thus start the motor, each cylinder firing thereafter in regular 35 order, the rod x having been moved back again to normal position to close the valves.

What we claim is:—

The combination with the cylinder of an internal combustion motor, of a reservoir 40 for combustible, a pipe connection extending therefrom to a cylinder of the motor, a valve in said pipe having a pocket or recess to receive the combustible, and means to actuate the valve whereby said pocket or 45 recess may be placed, when the valve is in one position, in communication with the reservoir and cut off from the cylinder, and in another position in communication with the cylinder and cut off from the reservoir, 50 there being a vent passage in the valve adapted to be placed in communication with the cylinder, when the pocket in the valve is also in communication therewith.

JAMES FRANK DURYEA.
